METHOD AND APPARATUS FOR SEALING
VITREOUS VESSELS

Daniel S. Gustin, Bloomfield, N. J., assignor to
Westinghouse Electric & Manufacturing Company,
East Pittsburgh, Pa., a corporation of
Pennsylvania

Application December 1, 1939, Serial No. 307,055

18 Claims. (Cl. 176—2)

This invention relates to the sealing of vitreous vessels, and more particularly to tipping off exhaust tubes of incandescent electric lamps containing gas at a pressure higher than atmospheric.

The principal object of my invention, generally considered, is the tipping off of the exhaust tubes of incandescent electric lamps which have been filled with gas at a pressure of higher than atmospheric.

Another object of my invention is the provision of a method and apparatus for tipping off exhaust tubes while enclosed in a space, defined by a reentrant flare tube and a closure member including electrodes for effecting the tipping off operation.

A further object of my invention is the employment of high frequency electric power for tipping off the exhaust tubes of vitreous vessels.

A still further object of my invention is the tipping off of exhaust tubes of incandescent electric lamps short of the flare tube opening of such lamps, whereby there is no sharp projecting portion of said tube outside of the lamp bulb outline after completion.

Other objects and advantages of the invention, relating to the particular arrangement and construction of the various parts, will become apparent as the description proceeds.

Referring to the drawing:

Fig. 1 is an elevational view of a lamp constructed in accordance with my invention, with portions broken away to more clearly illustrate the interior construction.

Fig. 2 is an enlarged sectional view of the flare tube and neck portion of a lamp as shown in Fig. 1, with apparatus in place for effecting the operation of tipping off the exhaust tube of said lamp, the power supplied being diagrammatically indicated.

Fig. 3 is a transverse sectional view on the line III—III of Fig. 2 in the direction of the arrows.

In my copending application, Ser. No. 144,143, filed May 22, 1937, now Patent No. 2,213,100, granted September 17, 1940, and owned by the assignee of the present application, I describe a method and machine for sealing vitreous vessels which contain gas at a pressure higher than atmospheric, in a manner which prevents the exhaust tube from blowing out during the tipping-off operation. In that case I provide a special chamber which is disposed about a portion of the exhaust tube, and in which a pressure above atmospheric, or corresponding with the pressure

in the lamp, is provided and the sealing off is effected by means of gas fires in said chamber.

In accordance with my present invention, I eliminate the necessity for such a special pressure chamber for such a purpose, by using the flare tube of the lamp itself, merely closing off the open end thereof and providing electrodes which extend into said flare tube and upon which suitable electric power is impressed, whereby the tube is not only sealed off under pressure, but the tip is made inwardly of the flare tube opening, thereby avoiding the undesirable projection of a relatively sharp portion beyond the flare tube.

The electric power employed is preferably ultra high frequency, say from ten to sixty megacycles, at a potential of 100 k. v., whereby the dielectric loss in the tube disposed between the adjacent ends of electrodes will serve to soften it sufficiently for the tipping-off operation. However, other electrical heating means, such as that due to resistance, may be employed instead.

Referring to the drawing in detail, like parts being designated by like reference characters, there is shown a gas-filled lamp 11, comprising a vitreous or glass envelope 12, having a reduced, generally cylindrical, neck portion 13, to which is sealed the usual flare tube 14, from the press 15 of which extends an arbor 16, and supporting leads 17 and 18, between which extends a tungsten filament 19 which, in the present embodiment, is of the coiled coil type. The arbor 16 is shown with a button 21 from which extend bracing wires 22 and 23 to the leads 17 and 18, and a supporting wire 24 to the filament 19.

In Fig. 1 the lamp 11 is shown provided with a medium screw base 25, and the exhaust tube 26 thereof is shown terminating short of the opening 27 to the reentrant portion provided by the flare tube 14.

Referring now to Figs. 2 and 3, the flare tube opening 27 is shown closed by apparatus 20, including resilient gasket means 28, preferably formed of rubber, and slidable electrodes 29 and 31 provided with their adjacent end portions 32 and 33 extending diagonally through a corresponding aperture in the gasket 28 into the chamber, defined by said closure apparatus and the flare tube 14, and engaging opposite sides of the exhaust tube 26, at a point sufficiently remote from the gasket 28 that the localized heating provided will not cause injury thereto, during the short period of time needed for the tipping off of said exhaust tube. The lower end of the exhaust tube 26 is shown received in a compression rubber 34, corresponding with that desig-

nated by the reference character 12 in my copending application, previously referred to.

The closure device 20 desirably comprises arms 30 and 40 pivoted in a manner disclosed in the Holloway application, Ser. No. 297,089, filed Sept. 29, 1939, and owned by the assignee of the present application, and operated by means of a lever, not shown, corresponding with that designated 44 in said application, so that said arms may be separated in order to permit reception of the exhaust tube 26 between the end portions thereof, notched as indicated at 53, and allow for the separation of the electrodes 29 and 31 for the same purpose.

The electrodes 29 and 31 are movable toward and away from one another in suitable slots, 35 and 36, one in each of the closure parts 30 and 40, the fit therein being sufficiently close to avoid any substantial leakage of air thereby. In order to urge said electrodes into engagement with the exhaust tube 26, after the ends of the parts have been brought together, springs 37 and 38 are provided acting between shoulder portions formed by depending flanges of angular clips 39 and 41, secured to the electrodes, and corresponding upstanding flanges 42 and 43 of angular portions secured to the closure parts 30 and 40.

The portions 39 and 41 on the electrodes are normally spaced from corresponding stop surfaces 44 and 45 on the closure parts 30 and 40 so that they can move together the desired amount for sealing off an exhaust tube 26, but will not move into actual contact with one another. The electrodes 29 and 31 are connected to a suitable source of power, represented by the secondary winding 46 of transformer 47, by means of leads 48 and 49, said power being preferably ultra high frequency of more than ten megacycles, and preferably of the order of fifty megacycles, at a potential of about 100 kilovolts.

The mode of operation of tipping off a lamp, when disposed as shown in Figs. 2 and 3, is to effect an exhaust and filling of the bulb 12 thereof, with the desired inert gas, as described more in detail in my copending application previously referred to, through the exhaust tube 26. After being filled with inert gas to the desired super-atmospheric pressure, the arms 30 and 40 are brought together to engage the tube 26, as shown in Figs. 2 and 3, and compressed air is admitted to the chamber 51 defined by the flare tube 14 and the closure parts 30 and 40, as by means of tube 52, until the pressure in said chamber approximates, or preferably exceeds, that in the bulb 12. The exhaust tube 26 passes through the notched portions 53 in the closure apparatus 20 with small enough clearance, so that there is relatively little leakage out of the chamber 51.

Ultra high frequency electrical energy is then impressed on the electrodes 29 and 31, causing a heating of that portion 54 of the exhaust tube immediately between the engaged ends 32 and 33 of said electrodes, either due to the dielectric loss in said tube, previously referred to, or a discharge or arc between said electrodes which may envelop that portion of the tube therebetween, or to more than one of these actions, depending on the voltage, frequency and conductivity of the tube, whereby said exhaust tube portion rapidly softens and is squeezed to effect a tipping off thereof by inward movement of the electrodes 29 and 31 under the influence of the actuating springs 37 and 38. When this has been effected, the tipped-off lamp is removed, either by the op-

erator, or automatically as described in the Holloway application previously referred to.

Although a preferred embodiment of my invention has been disclosed, it will be understood that modifications may be made within the spirit and scope of the appended claims.

I claim:

1. The method of sealing a vitreous vessel having an exhaust tube extending from a re-entrant portion, comprising closing said re-entrant portion around said tube, creating a gas pressure above atmospheric in said closed space, and electrically tipping off at a portion of said tube while subjected to said pressure.
- 10 2. The method of sealing a vitreous vessel, having an exhaust tube extending from a re-entrant portion, comprising disposing electrodes so that their adjacent ends engage said exhaust tube inwardly of the open end of said reentrant portion, creating a gas pressure above atmospheric around said engaging ends, and energizing said electrodes by means at high frequency to tip off said exhaust tube inwardly of said opening.
- 20 3. The method of sealing a vitreous vessel, having an exhaust tube extending from a re-entrant portion, comprising disposing electrodes so that their adjacent ends engage said exhaust tube inwardly of the open end of said reentrant portion, creating a gas pressure above atmospheric in said reentrant portion, and energizing said electrodes to tip off said exhaust tube.
- 25 4. The method of sealing a vitreous vessel having an exhaust tube extending from a re-entrant portion, comprising closing said re-entrant portion around said tube by means including electrode portions extending into said reentrant portion, admitting compressed air to said reentrant portion around said electrodes and tipping off by applying electrical energy to said electrodes.
- 30 5. The method of sealing a vitreous vessel having a tubular extension from a reentrant portion, after said vessel has been filled with a gas above atmospheric pressure, comprising closing said reentrant portion around said extension, creating gas pressure above atmospheric in said reentrant portion, and tipping off the enclosed portion of said extension while subjected to said pressure.
- 35 6. The method of sealing off a lamp having an exhaust tube extending from a reentrant portion, comprising closing said reentrant portion around said tube by means including electrode portions engaging said tube in said reentrant portion, exhausting, and filling said lamp through said tube with gas above atmospheric pressure, creating in said reentrant portion a gas pressure at least as high as that in said lamp, and applying high frequency energy to said electrodes to effect a tipping-off operation in said reentrant portion.
- 40 7. Apparatus for tipping off exhaust tubes extending from reentrant portions of vessels containing gas at a pressure higher than atmospheric, comprising closure means for said reentrant portions, including electrodes the adjacent ends of which extend into said reentrant portions, means for creating a gas pressure above atmospheric in said reentrant portions, and means for applying electrical energy to said electrodes to effect a tipping-off operation.
- 45 8. Apparatus for tipping off exhaust tubes extending from reentrant portions of vessels containing gas at a pressure higher than atmos-

pheric, comprising closure means for said re-entrant portions including electrodes, said closure means being formed as end portions of pivoted arms, whereby it is adapted to encircle an exhaust tube, with the electrodes engaging opposite sides thereof in a reentrant portion, means for creating a gas pressure above atmospheric in said reentrant portion, and means for applying electrical energy to said electrodes to effect a tipping-off operation.

9. Apparatus for tipping off an exhaust tube extending from a reentrant portion of a vessel containing gas at a pressure higher than atmospheric, comprising closure means for said reentrant portion, including resilient gasket means adapted to engage the adjacent end of said vessel, a pair of electrodes slidable in said closure means and having their adjacent portions extending diagonally through an aperture in said gasket means to engage said exhaust tube on opposite sides thereof, means for creating a gas pressure above atmospheric in said reentrant portion and means for applying electrical energy to said electrodes to effect a tipping-off operation.

10. Apparatus for tipping off an exhaust tube extending from a reentrant portion of a vessel, comprising closure means for holding gas pressure in said reentrant portion, a pair of electrodes slidable in said closure means and having their adjacent portions extending diagonally toward one another and into said reentrant portion to engage said exhaust tube on opposite sides thereof, and means for effecting a tipping-off operation therein by means of ultra high frequency electrical energy.

11. The method of sealing vitreous vessels having an exhaust tube extending in a reentrant portion, comprising creating a gas pressure above atmospheric in said reentrant portion and electrically tipping off said tube in said reentrant portion while subjected to said pressure.

12. The method of sealing a vitreous vessel having a tubular extension in a reentrant portion, comprising creating gas pressure above atmospheric in said reentrant portion and tipping off said extension in said reentrant portion while subjected to said pressure.

13. Apparatus for tipping off exhaust tubes extending in reentrant portions of vessels containing gas at a pressure higher than atmospheric, comprising means for creating a gas pressure higher than atmospheric in said reentrant portions, and means for tipping off said exhaust tubes at points within said reentrant portions while subjected to said pressure.

14. Apparatus for tipping off exhaust tubes extending from reentrant portions of vessels containing gas at higher than atmospheric pressures, comprising means for closing said reentrant portions, means for creating a gas pressure above atmospheric in said closed portions, and means for applying energy to said exhaust tubes in said reentrant portions for effecting tipping-off operations.
15. The method of sealing a vitreous vessel having an exhaust tube, comprising enclosing only a portion of said tube in a chamber, creating a gas pressure above atmospheric in said chamber, disposing electrodes with their adjacent ends engaging opposite sides of a portion of said tube in said chamber, and causing an electrical discharge between said electrodes to heat said tube for tipping it off therein.
16. The method of sealing a vitreous vessel having an exhaust tube comprising enclosing only a portion of said tube in a chamber disposed close to said vessel and defined in part by wall portions thereof, creating gas pressure above atmospheric in said chamber, disposing electrodes with their adjacent ends engaging opposite sides of a portion of said tube in said chamber, and causing an electrical discharge between said electrodes to heat and tip off the tube therein.
17. The method of sealing a vitreous vessel having an exhaust tube comprising enclosing only a portion of said tube in a chamber, creating a gas pressure above atmospheric in said chamber, disposing electrodes with their adjacent ends directed toward said vessel, so as to engage opposite sides of a portion of said tube close to said vessel and in said chamber, and causing an electrical discharge between said electrodes to heat said tube and tip it off in said chamber, leaving only a short length on said vessel.
18. The method of sealing a vitreous vessel having an exhaust tube comprising enclosing only a portion of said tube in a chamber defined in part by wall portions of said vessel, creating a gas pressure above atmospheric in said chamber, disposing tipping off elements with their adjacent ends directed toward said vessel, so as to engage opposite sides of a portion of said tube in said chamber and disposed close to said vessel, and applying heat to said exhaust tube by means of said elements to tip it off in said chamber and leave only a short length on said vessel.
